DESIGN FOR A COMBINATION SHAKER AND DECANTER

Edward Kanter, Cleveland Heights, Ohio

Application August 14, 1933. Serial No. 49,019

Term of patent 7 years

To all whom it may concern:

Be it known that I, EDWARD KANTER, a citizen of the United States, residing at Cleveland Heights, in the county of Cuyahoga and State of Ohio, have invented a new, original, and ornamental Design for Combination Shaker and Decanter, of which the following is a specification, reference being had to the accompanying drawing, forming part hereof, wherein Fig. 1 is a side elevation of a combination shaker and decanter showing my new design; and Fig. 2 is a top plan view of the same.

The circular elements disclosed in Fig. 1 indicate openings in an outer metal casing, which enclose an inner glass container. These openings are placed in the metal casing so that the contents of the glass container will be visible therethrough.

I claim:—

The ornamental design for a combination shaker and decanter substantially as shown and described.

EDWARD KANTER.
